COATING APPLYING MACHINE

Wilbur L. MacKenzie, Beverly, Mass., assignor to
United Shoe Machinery Corporation, Paterson,
N. J., a corporation of New Jersey

Application February 25, 1935, Serial No. 8,004

26 Claims. (Cl. 12—80)

My invention relates to machines for applying adhesive coatings, more particularly to shoe-soles. The embodiment of the invention illustrated herein is adapted for the temporary attachment of 5 a heel-breast-flap to the body of a sole from which it has been divided. An application for Letters Patent of the United States, disclosing another embodiment of the invention and containing claims generic to the present case is filed simultaneously herewith, it having the title Coating machine and bearing the Number 8,003.

It is a common practice in connection with women's shoes to split from the grain-side of a sole a thin flap, which may later be cemented to 15 the breast of a heel attached to the shoe, to furnish a covering for said breast. Between the splitting and breast-covering operations, various other manufacturing steps occur involving the sole. For example, in a cement-process shoe, 20 there are the operations of shank-reducing, roughing of the flesh-side, the application of cement and then a solvent thereto, and the pressing of the sole upon the shoe-bottom. While this is being done, the rather frail, loose breast-flap is obviously liable to injury, as by creasing 25 or tearing. It is an object of my invention to guard against difficulties of this character, and with this in view I have provided a machine which may, among its various uses, be employed to temporarily attach a breast-flap to the opposed surface of its sole, to be separated therefrom when it is to be cemented to the heel-breast.

For the attainment of the above object, I combine, as a feature of the invention and in a novel 35 manner, a turning member in engagement with which a sole is advanced to separate the breast-flap therefrom, and a cement-applying member into co-operation with which the separated surfaces are carried in the continued advance of 40 the work. Preferably, the application of the adhesive is to a portion only of the sole-surface. By successive steps the work is thus prepared for the coating and said coating applied. Thereafter, the attaching operation may be completed 45 by the action of means which brings the separated surfaces together and applies pressure thereto. The heel-breast-flap is in this way held to the body of the sole, so it will not be liable to injury, as it would if loose. Yet when the 50 flap is to be cemented to the heel-breast it may readily be freed from the sole-body by the operator, who can grasp the uncoated portion and separate the entire flap. The particular instrumentalities herein illustrated for performing the successive operations upon the work include a supporting table along which extends a curved flap-turning plate, a pair of rolls receiving the work from the plate and to one of which rolls cement is supplied, and a pair of pressure-rolls 55

situated at one side of the cementing rolls. As already indicated, this combined work-arranging, cementing and pressing means and its sub-combinations are not necessarily limited to their use for sole-flap-attachment, but may be novel in 5 other connections.

In operations of this sort, in which separated surfaces are pressed together, the work-portions are liable to be displaced laterally with relation to each other, especially when one, as a flap divided from a sole, is thin. Another feature of my invention guards against such displacement. With coating and pressing means for work-pieces, between which pressing means and work-pieces there is relative movement longitudinally of the 15 coated surface, I associate means contacting yieldably with the opposite edges of the pieces at the pressing means to prevent their displacement during the relative longitudinal movement. The members furnishing the work-contacting means 20 may be positioned by engagement with one work-piece while they are positioning another work-piece. This work-positioning means may further be controlled by actuating means for the pressure member, as through connections to a treadle 25 or other operator-governed member by which the pressure members are caused to engage the work. In this way, the positioning members may be held inactive to receive the coated work-pieces while the pressure members are separated, and then 30 freed to exert their work-positioning effect when the pressure members are rendered active.

A particular embodiment of the invention is shown in the accompanying drawings, in which 35

Fig. 1 is a front elevation of my improved machine, portions being broken away;

Fig. 2, a top plan view taken below the applying roll;

Fig. 3, a vertical sectional detail of the coating 40 rolls and pressure-rolls; and

Fig. 4, a detail in side elevation of said pressure-rolls, illustrating the last operation upon the work.

Upon a frame 10 is carried a horizontal work-supporting table 12. Extending along this table, between the opposite sides, is a flap-turning plate 14. The plate may be secured to the table by a downward extension 16, which holds its lower edge so spaced at 18 from the work-supporting surface that the body-portion of the rear of a sole S from which a heel-breast-flap f has been divided may be slid beneath it over the table from front to rear of the machine. The plate 14 is curved reversely, first extending upwardly and rearwardly of the machine at a, then turning at b and curving forwardly and downwardly at c. Consequently, if the heel-end of a sole with a breast-flap loose upon it is inserted beneath the plate, as indicated in dash-dot lines in Fig. 2, 55

the flap will pass above the plate at its outer side and be turned up by it to clear the sole-body. Then, as the work is advanced from right to left (Fig. 2), it will be folded back over the body as appears in Fig. 3. The work is thus prepared for the application of an adhesive to the surface *s* from which the flap *f* has been separated.

Beyond the table 12, in the direction in which the work is advanced by the operator, is a cement-applying mechanism M. This may consist of a lower work-supporting roll 20 and an upper applying roll 22, the latter being shown as provided with pockets in which the cement may be held for application to the work. The rolls are geared at 24 to rotate together, in the directions indicated by the arrows in Fig. 1, from a source of power not appearing. The cement may be supplied to the applying roll from a receptacle 26 mounted upon the top of the frame and delivering through a valve 28. The lower roll is shown as held yieldably up to urge the work against the applying roll, which is journaled horizontally in the frame, by a spring 30 acting upon a depending arm of a lever 32 in which said roll turns. The bite of the rolls 20 and 22 is horizontally aligned with the space 18 between the table and plate but is so located transversely with respect to the lower edge of the plate, that, as the sole leaves said plate and passes between the rolls, the rear portion of the surface *s* will, as is illustrated in full lines in Fig. 2, project at *u* beyond the rolls so it will remain uncoated, while the remainder of the surface to a line adjacent to the juncture of the flap and the sole will receive an application of the adhesive.

The work is now ready for the pressing of the flap *f* against the surface *s* upon its further advance, this being in another direction from that for flap-turning and cementing. Situated at one side of the rolls 20 and 22 of the applying mechanism, with their axes substantially at right angles to the axes of the coating rolls, are horizontal lower and upper pressure-rolls 34 and 36, the bite of the latter rolls being preferably somewhat below that of the coating rolls. The lower roll 34 is shown as journaled in a standard 38 rising from the bottom of the frame 10. The roll 36 turns about a spindle 40 projecting inwardly from an arm 42 pivoted upon the frame. Both of these pressure-rolls may be idle. Pivoted to the arm 42 is a rod 44 joined to a treadle 46. A spring 48, interposed between the frame and a collar 50 fast upon the rod, holds the roll 36 normally raised clear of the roll 34 to an extent determined by the contact with the frame of a stop-collar 52 upon the rod. By depression of the treadle, the roll 36 may be lowered into contact with work with its coating of cement, which is carried between the rolls 34, 36 by the operator from the rolls 20 and 22. To prevent the flap *f* from passing to the outer or forward side of the roll 36, and to prepare it for being laid upon the sole-surface *s*, the spindle 40 has a head 54. This appears as tapering from the diameter of the roll 36 downwardly to a somewhat rounded end, which overlaps but is spaced outwardly from the portion *c* of the plate 14 at a point just above the space 18. Therefore, as the sole in its advance is about to pass beyond the plate 14 and enter between the cementing rolls 20 and 22, the flap contacts with the inclined surface of the head 54 and is thereby directed above the pressure-roll 36. When the work has reached the

full-line-position of Fig. 2, the operator may depress the treadle 46 to lower the roll 36. Then he may draw the sole outwardly between the rolls 34 and 36 at right angles to the direction of its previous travel. In this movement, engagement of the flap with the roll 36 lays said flap down gradually upon the surface *s* of the sole, and the opposite pressure of the two rolls is sufficient to produce the desired adhesion of the flap to the sole-body. 10

As the flap may be rather flaccid, it is liable to lateral displacement at the pressure-rolls 34 and 36, so it might not be laid properly but be creased or otherwise mutilated in its passage between the rolls. This I avoid in the following manner: Just at the rear of the pressure-rolls is located a pair of flap-positioning members shown as furnished by arms 60 and 62. These are pivoted at 64 upon the frame to swing independently of each other. They are yieldably drawn toward each other by a spring 66 connecting them. The normal position of the pair of arms is under the control of treadle mechanism. To this end, to the collar 50 upon the treadle-rod 44 is pivoted one arm of a bell-crank-lever 70 fulcrumed upon the frame. To the other arm of this lever is articulated a link 72 provided with a horizontal slot 74 in which lies a projection 68 from the arm 62. When the treadle 46 and its rod are in their initial raised relation, the outer end of the slot, by contact with the projection, limits the anticlockwise movement of the arm 62 (Fig. 1). At the same time, the spring 66 urges the arm 60 in a clockwise direction, the extent of this movement being determined by engagement of said arm 60 with a projection 76 from the frame. The spring also holds the projection 68 against the slot-end. A depression 78 at the upper extremity of the arm 60 now lies in a plane just above the roll and not greatly removed from its longitudinal center. The upper end of the companion arm, which has a like depression 78, will be below the top of the roll. As the operator advances the work, with its coating of cement, from the rolls 20 and 22 between the rolls 34 and 36, the forward edge of the sole will strike the arm 60 at the depression 78, said arm yielding as the spring 66 elongates until the entire width of the sole is in position to receive contact of the rolls 34 and 36 as the operator draws it forward. At this time the treadle is depressed to lower the upper roll 36 upon the work. The end of the slot in the link 72 is thereby carried away from the projection 68, so the spring 66 is allowed to draw the arm 62 at the depression 78 against the inner edge of the sole. As a result of this engagement, as the operator pulls the work toward him, both arms bear yieldably against the opposite edges of the flap under the guidance of the edges of the sole-body. The flap is consequently maintained correctly positioned across the sole as it approaches the pressure-rolls and its smooth laying is assured. 40

To outline the course followed in the use of the machine, the operator, facing it at the side toward the observer in Fig. 1, takes a shoe-sole with its heel-portion split to furnish a flap *f* intended for later attachment to a heel-breast, and inserts the body-portion of the sole at the rear over the table 12 into the space 18 beneath the plate 14 70 at the portion *a* thereof. This is as seen in dash-dot lines in Fig. 2. Contact with the plate turns up the flap from the sole-surface *s*, and the extent of movement of the work in this direction may be determined by the engagement of the 75

5 Juncture of the flap and sole-body with the lower edge of the plate. With the flap thus raised, the operator moves the sole along the table and plate to the left toward the rolls 20 and 22, which are in rotation. The curvature of the plate gradually bends the flap away from the sole-body through more than 90°, holding it clear of the roll 22. Between this roll and the lower roll 20, the heel-portion of the sole now passes to receive a coating 10 of cement over the surface s , but not at the extreme rear, where the area u extends beyond the inner end of the roll 22 so that it is left uncoated. Continued advance of the work brings it between the pressure-rolls 34 and 36, the mounting 15 of which is such as to leave an uninterrupted space at their inner ends through which the work may be introduced. The flap is maintained at the rear of these rolls by its engagement with the inclined surface of the head 54 before it leaves the plate 14 and the rolls 20 and 22. As the work enters between the pressure-rolls, the positioning arm 60 is engaged by the forward edge of the sole and is shifted as the operator enters said sole longitudinally of the rolls to the desired extent. Depression 20 of the treadle 46 causes the roll 36 to descend upon the sole in advance of the flap and effects the release of the positioning arm 62 by movement of the link 72. The elements directly co-operating with the work are as seen at the left 25 of Fig. 2. The attachment is completed as the operator draws the work out between the rolls 34 and 36, which press the flap upon the coated surface. In this movement, said flap is held in registration with the sole-body by the engagement 30 of the arms 60 and 62 at their edges. These arms are maintained by the sole itself in the proper relation to effect this and are free to adapt themselves transversely of the sole to whatever position it may occupy. Thus secured to the sole- 35 surface s , the flap is protected against tearing or distortion during succeeding operations, yet when it is to be secured to the heel-breast, it may easily be detached from the sole-body by grasping it at the portion over the uncoated area u and drawing 40 the remainder away from the sole.

Having described the invention, what I claim as new and desire to secure by Letters Patent of the United States is:

1. In a machine for cementing soles having flaps, a turning member in engagement with which a sole is advanced to separate the flap therefrom, and a cement-applying member into co-operation with which is carried in continued advance of the work a portion only of the sole-body from which 55 the flap has been separated.

2. In a machine for cementing soles having flaps, a turning member in engagement with which a sole is advanced to separate the flap therefrom, a cement-applying member into co-operation with which the separated surfaces are carried in continued advance of the work, and means for bringing the separated surfaces together and applying pressure thereto during further advance of the work in another direction 60 than that during which occurs the application of cement.

3. In a machine for cementing soles having flaps, a support over which a sole is advanced, a flap-turning plate extending along the support 70 and separated therefrom, and a cement-applying member co-operating with the forward extremity of the plate above the support.

4. In a machine for cementing soles having flaps, a support over which a sole is advanced, a flap-turning plate extending along the support 75

and separated therefrom, a cement-applying member co-operating with the forward extremity of the plate, and a pair of pressure members engaging the sole and flap at one side of the applying member. 5

5. In a machine for cementing soles having flaps, a support over which a sole is advanced, a flap-turning plate extending along the support and separated therefrom, a cement-applying member co-operating with the forward extremity 10 of the plate, and pressure means for the sole and flap situated at one side of the applying member, a portion of said pressure means overlapping the plate.

6. In a machine for cementing soles having 15 flaps, a support over which a sole is advanced, a flap-turning plate extending along the support and separated therefrom, a cement-applying member co-operating with the forward extremity 20 of the plate, and a pair of pressure members engaging the sole and flap at one side of the applying member, one of said pressure members having a reduced end portion overlapping the plate.

7. In a machine for attaching heel-breast-flaps to soles from which they have been divided, 25 a flap-turning member, and a cement-applying member to which the work is advanced for coating while the turning member holds back the flap, said applying member operating upon the sole between the connection thereof to the breast-flap and an area at the rear of the sole which is left uncoated. 30

8. In a machine for attaching heel-breast-flaps to soles from which they have been divided, a flap-turning member, a cement-applying member 35 to which the work is advanced for coating while the turning member holds back the flap, said applying member operating upon the sole between the connection thereof to the breast-flap and an area at the rear of the sole which is left 40 uncoated, and pressure means engaging the sole and flap while said flap is still under the influence of the turning member.

9. In a machine for attaching heel-breast-flaps to soles from which they have been divided, a flap-turning member, a cement-applying member to which the work is advanced from the turning member for coating, said applying member operating upon the sole between the connections 50 thereof to the breast-flap and an area at the rear 55 of the sole which is left uncoated, and pressure means acting upon the sole and flap during movement in a direction substantially at right angles to the movement of the work at the applying member. 55

10. The combination with a table, of a plate extending above the table and spaced therefrom to admit a sole, said plate being curved along the table to turn a flap upon the sole, and a cement-applying roll acting upon the sole at the end of 60 the plate.

11. The combination with a table, of a plate extending above the table and spaced therefrom to admit a sole, said plate being curved along the table to turn a flap upon the sole, a pair of rolls 65 having their bite alined with the space between the table and plate, and means for delivering cement to one of the rolls.

12. The combination with a table, of a plate extending above the table and spaced therefrom 70 to admit a sole, said plate being curved along the table to turn gradually a flap upon the sole, a cement-applying roll acting upon the sole at the end of the table, and a pair of pressure members situated beyond the table at one side of the roll. 75

13. The combination with a table, of a plate extending above the table and spaced therefrom to admit a sole, said plate being curved upwardly and forwardly along the table to turn gradually 5 a flap upon the sole, a pair of rolls having their bite alined with the space between the table and plate, means for delivering cement to one of the rolls, and a pair of pressure-rolls situated at one side of the first-mentioned rolls.
14. The combination with a table, of a plate extending above the table and spaced therefrom to admit a sole, said plate being curved upwardly and forwardly along the table to turn gradually 10 a flap upon the sole, a pair of rolls having their bite alined with the space between the table and plate, means for delivering cement to one of the rolls, and a pair of pressure-rolls situated at one side of the first-mentioned rolls and presenting an uninterrupted space between them at the ends 15 toward the table to receive the work therefrom in a direction longitudinally of the axes.
15. In combination, means for coating a work-piece, pressure members arranged to act at opposite faces of the work-piece and between which and said work-piece there is relative movement 20 longitudinally of the coated surface to force another piece against it, and members contacting with the opposite edges of the pieces at the pressure means to prevent their relative displacement.
16. In combination, means for coating a work-piece, pressure members arranged to act at opposite faces of the work-piece and between which and said work-piece there is relative movement 25 longitudinally of the coated surface to force another piece against it, and members at the pressure members positioned by engagement with opposite edges of one work-piece and positioning the other work-piece by engagement therewith during the relative longitudinal movement.
17. In a cementing machine, means for coating a work-piece, pressure members arranged to act at opposite faces of the work-piece and between which and said work-piece there is relative movement 30 longitudinally of the coated surface to force another piece against it, and members contacting with the opposite edges of the pieces at the pressure members and yieldable with respect to each other to prevent the relative displacement of said pieces during the relative longitudinal movement.
18. In a cementing machine, means for coating a work-piece, means to which the coated piece is advanced for pressing another piece against the coated surface, a member lying in the path of the work at the pressing means for contact with the edges of the pieces at one side, and a member joined to said contact member for movement against the opposite edges of the pieces.
19. In a cementing machine, means for coating a work-piece, means to which the coated piece is advanced for pressing another piece against the coated surface, a member lying in the path 55 of the work at the pressing means for contact with the edges of the pieces at one side, a member movable against the opposite edges of the pieces, and a spring joining the members to transmit the movement of the first to the second.
20. In a cementing machine, means for coating a work-piece, means for pressing another 60
- piece against the coated surface, means for actuating the pressure means, and means contacting with the opposite edges of the pieces at the pressure means and controlled by the actuating means to prevent the relative displacement of 5 said pieces.
21. In a cementing machine, means for coating a work-piece, opposite pressure members between which the coated piece is delivered, actuating means for causing the pressure members 10 to engage the work, and work-positioning members for engagement with the edges of the work at the pressure members, said positioning members being controlled by the actuating means.
22. In a cementing machine, means for coating a work-piece, opposite pressure members between which the coated piece is delivered, an operator-controlled member for moving one of the pressure members toward the work, work-positioning arms for engagement with the opposite edges of the work, and connections to the operator-controlled member for holding the arms for the reception of the work.
23. In a cementing machine, means for coating a work-piece, opposite pressure-rolls between 25 which the coated piece is delivered, one of said rolls being movable toward and from the other, a treadle-rod connected to the movable roll, a pair of spaced work-positioning arms pivoted for co-operation with the rolls, a stop limiting the 30 movement of one of the arms, connections between the treadle-rod and the other arm, and a spring joining the arms.
24. In a cementing machine, means for coating a work-piece, opposite pressure-rolls, between 35 which the coated piece is delivered one of said rolls being movable toward and from the other, a treadle-rod connected to the movable roll, a pair of spaced work-positioning arms pivoted for co-operation with the rolls, a stop limiting the 40 movement of one of the arms, connections between the treadle-rod and the other arm for holding said other arm normally inactive, and a spring joining the arms and holding the movement-limited arm against its stop.
25. In a machine for attaching heel-breast-flaps to soles from which they have been divided, a flap-turning member, a cement-applying member to which the work is advanced from the turning member for coating, said applying member operating upon the sole between the connection thereof to the breast-flap and an area at the rear of the sole which is left uncoated, pressure means for engagement with the sole and flap, and flap-positioning members contacting with the opposite edges of the sole at the pressure means.
26. In a machine for attaching heel-breast-flaps to soles from which they have been divided, a flap-turning member, a cement-applying member to which the work is advanced from the turning member for coating, said applying member operating upon the sole between the connection thereof to the breast-flap and an area at the rear of the sole which is left uncoated, 60 a pressure member for engagement with the sole and flap, and flap-positioning members contacting with the opposite edges of the sole at the pressure member and yieldable from each other under the influence of the sole.

WILBUR L. MACKENZIE.

CERTIFICATE OF CORRECTION.

Patent No. 2,046,421.

July 7, 1936.

WILBUR L. MACKENZIE.

It is hereby certified that error appears in the printed specification of the above numbered patent requiring correction as follows: Page 4, first column, line 27, claim 15, for "members" read means; line 29, same claim, for "means" read members; and that the said Letters Patent should be read with these corrections therein that the same may conform to the record of the case in the Patent Office.

Signed and sealed this 20th day of October, A. D. 1936.

Leslie Frazer
Acting Commissioner of Patents.
